UNITED STATES PATENT OFFICE.

LEWIS J. ATWOOD, OF WATERBURY, CONNECTICUT, ASSIGNOR TO THE PLUME & ATWOOD MANUFACTURING COMPANY, OF SAME PLACE.

WICK-TUBE FOR LAMPS AND LAMP-STOVES.

SPECIFICATION forming part of Letters Patent No. 357,545, dated February 8, 1887.

Application filed January 12, 1882. Serial No. 49,937. (No model.)

To all whom it may concern:

Be it known that I, LEWIS J. ATWOOD, of Waterbury, in the county of New Haven and State of Connecticut, have invented an Improvement in Wick-Tubes for Kerosene Stoves and Lamps, of which the following is a specification.

My invention is for maintaining the wick-tube complete, with only the small openings for the wick-raisers, for stiffening the wick-tube, for preventing wear at the bearings for the wick-raising shaft, and for excluding air from the housing or ratchet-case, and for strengthening the wick-tube and lessening the cost of its construction.

In the drawings, Figure 1 is a vertical section of the wick tube and case. Fig. 2 is a horizontal section at the line *x x*, and Fig. 3 is an elevation.

20. The wick-tube *a* is made of sheet metal, with the edges folded back to form flanges 2 2, and a clamping-strip, *b*, slipped endwise over the folded edges and closed by pressure. This joint is made at one or both edges of the wick-tube and stiffens the same, so that it is not liable to bend, and the sides of the wick-tube can be made otherwise complete before the parts are put together. If the projecting flanges 2 only are used, they stiffen the wick-tube, and they may be united by rivets or solder.

35. In one side of the wick-tube there are slots for the wick-raising wheels *d*, and there may be three or more such wheels. I have represented five of these wheels *d* upon the shaft *e*, and at the outer end of such shaft there is the thumb-wheel *f*, that is made of sheet metal, with the edge returned in a cylindrical form, so as to give a sufficient surface to prevent injury to the fingers in turning the wick-raisers and raising or lowering the broad wick that is employed in this burner.

40. I employ a separate housing or case, *o*, having rounded ends, so as to be stamped up out of one piece of metal, and its flanges *o'* are riveted, interlocked, or soldered to the side of the wick-tube, such case being of a size to contain the wick-raising wheels. I also provide the necessary openings in the case for 45. the shaft *e* to pass through, and I introduce a separate tubular bearing, *i*, at one end of the case and a separate closed tubular cap, *l*, at

the other end of the case. These are soldered or otherwise secured in place. These tubular bearings form an extended surface for the shaft 55 and prevent the metal wearing away and the shaft becoming loose, as has heretofore been the case, and air is excluded from the wick-raiser case, and there is no risk of the wick catching fire within the case or of oil passing 60 out at the journals and catching fire. These tubular bearings are available with any ordinary wick-raiser shaft and with a housing made in one piece with the wick-tube. The end of the wick-tube is stiffened by turning 65 over the sheet metal to form a fold, as at *n*, and numerous small transverse corrugations are stamped in the metal to stiffen the same, and thereby allow for the use of thin metal, that will not conduct the heat down the wick-tube as rapidly as would be the case with 70 thicker metal.

I am aware that a cover for the wick-raisers has been made of a separate piece fastened upon the wick-tube; also, that the bearings for 75 the shaft of the wick-raiser have in some instances been segments of cylinders pressed up in the metal of the cover, and in some instances such shaft has passed through a stuffing-box upon the body of the burner. In some 80 instances the bearing for the shaft has been made of a spring with the end bent up into a cylindrical form. Circular and flat wick-tubes have been united by a hollow strip slipped over returned flanges; but where these are applied the flame is liable to be uneven in consequence of the projection interfering with the draft. I use such strip at the edge of the wick, where it stiffens the tube and does not interfere with the draft. 90

I claim as my invention—

The combination, with the wick-tube having a housing at one side, of the wick-raisers within such housing, the shaft for the same, and separate tubular bearings for the wick-raiser shaft introduced through the metal of the housing and secured, substantially as specified.

Signed by me this 2d day of January, A. D. 1882.

LEWIS J. ATWOOD.
